RADIO ANTENNA

John M. Beaufort and Howard S. Pyle,
Seattle, Wash.

Application May 2, 1938, Serial No. 205,605

2 Claims. (Cl. 250—33)

This invention relates to radio antennas, particularly to antennas of the mast type for use with radio apparatus installed on motor cars.

It is common practice in radio-equipped motor cars, such as police prowls cars, to mount a transmitting antenna at the rear of the car, or in some instances, on the running board or side of the body. Such antennas generally consist of a flexible metallic rod, arranged in two or three telescopic sections, so that it may be carried in a telescoped position or extended to any predetermined height by manually pulling the inner sections from the lower sections. It is accordingly exceedingly inconvenient to carry such an antenna in a normally telescoped position, and to manually extend it to the necessary height required each time the radio equipment is to be used. To do so means that the motor car must be stopped, the operator must leave his seat, extend the antenna and return to the radio operating position, reversing the process when the communication is finished. By reason of this inconvenience, it has become common practice for operators of such radio equipped motor vehicles to operate the motor car in transit with the antenna extended to the required height for normal radio operation, thereby constituting a hazard in that the average antenna is approximately eight feet long, and vertically mounted, causing it to extend to a point several feet above the roof level of the car. The antenna is accordingly endangered during travel of the vehicle, by overhanging limbs, low doorways and underpasses, and similar objects. Dependence is placed on the flexibility of the antenna mast for protection in such cases, it being expected that it will bend or give sufficiently to clear such objects, returning to an upright position by reason of its construction of a springy material. In actual practice, such an antenna is unsatisfactory.

With the above disadvantages in mind the present invention has for an object to provide an antenna formed of telescopically assembled sections which may be carried in normal transit in a telescoped position of such length that it offers no hazard such as accidental contact with fixed objects, and which may be instantly extended into any predetermined length by a fluid pressure medium controlled from the instrument panel of the vehicle.

A further object is to provide an antenna of this type which will be formed of a few strong simple and durable parts, which will be inexpensive to manufacture and install and which will not easily get out of order.

With the above and other objects in view the invention consists of certain novel details of construction and combinations of parts herein-after fully described and claimed, it being understood that various modifications may be re-

sorted to within the scope of the appended claims without departing from the spirit or sacrificing any of the advantage of the invention.

In the accompanying drawing forming part of this specification,

Figure 1 is a side elevation of an antenna constructed in accordance with the invention, in extended position, and provided with a rear bumper mounting bracket.

Figure 2 is an enlarged longitudinal sectional view of the antenna in telescoped position.

Referring now to the drawing in which like characters of reference designate similar parts in the various views, 10 designates the lower or main body of the mast antenna, the same preferably being formed of a metal tube or pipe which is provided at the bottom with a pipe flange 11 which in turn is secured to the top of a conventional insulator 12 through the medium of cap screws 13. An angular rear bumper mounting bracket 14 is secured to the bottom of the insulator and is provided with a U-bolt 15 for securing the antenna to the rear bumper of a motor vehicle.

The lower end of the body is formed airtight at its point of mounting on the insulator and forms an air chamber into which compressed air or gases are introduced through a suitable pipe nipple 16 which is threadedly engaged in an opening 17 in the side of the body directly above the pipe flange 11. Preferably the fluid pressure medium is conducted to the nipple from its source of supply by a suitable pipe connection 18 which is controlled by a suitable valve mechanism on the instrument board of the vehicle within convenient reach of the operator.

The top of the antenna body 10 is provided with a cap 19 which serves the dual purpose of forming a closure for the body and providing a guide for centering the intermediate section 20 of the antenna. The cap is provided with an opening 21 through which the intermediate section may freely move.

Disposed on top of the cap is a soft rubber gasket 22 which serves as a bumper for the intermediate section when the latter is lowered, thereby preventing an abrupt metal to metal shock when the center section telescopes. The seal also serves to prevent leakage of rain or other moisture into the inside of the antenna body 10 when the antenna is in its telescoped position.

The intermediate section 20 of the antenna is formed of a metallic tube or pipe similar to the body, and of sufficient diameter to slip easily within the body and provide sufficient clearance for a metal stop sleeve 23 which surrounds the lower end of the intermediate section and engages the inner face of the cap 19 to limit extending movement of the intermediate section relative to the body 10. The sleeve is held in place through

the medium of a bushing 24 which is threadedly engaged with the inner surface of the intermediate section. The bushing is provided with a collar 25 upon which the stop sleeve is supported.

5 A second bushing 26 is threadedly engaged with the inner surface of the bushing 24 and is provided with a central opening 27 of sufficient diameter to permit passage of compressed air or gas from the body 10 into the intermediate section in order to lift the tip section to extended position.

10 The bushing 26 is provided with a collar 28 which clamps a leather cup piston 29 against the collar 25 of the outer bushing 24. When air or gas is applied to the bottom surface of the cup piston the piston expands against the inner wall of the body 10 and forms an air seal which prevents the air or gas escaping past the piston so that pressure of the gas below the piston forces the intermediate section 20 to extended position.

15 A vent opening 30 is formed in the body 10 near the cap 19 to vent the interior of the body above the piston so that movement of the piston under urge of incoming compressed air or gas will not be impeded by the piston compressing air ahead of it against the cap 19.

20 A cap 31 is threadedly engaged with the top of the intermediate section 20 and is provided with a central guide opening 32 to receive the upper section 33 of the antenna mast. The upper section preferably is formed of a solid resilient rod adapted to yield when an obstruction is encountered and return to initial position after the obstruction is passed. A ball 34 is threaded on to 25 the top of the rod section to lend a finished appearance to the antenna.

25 A sleeve 35 is mounted on the lower end of the rod section 33 and is held in place by a nut 36 which is threaded on to the lower end of the rod section. The sleeve performs the dual function of weighting the rod section to promote quick gravitation thereof and at the same time performs the function of a stop which engages the cap 31 and limits extending movement of the rod section.

40 A flexible cup piston 37 is secured to the rod section 33 through the medium of a nut 38 which clamps the piston against the sleeve securing nut 36. The piston forms a seal in the intermediate section 20 past which no compressed air or gas can escape. Pressure of air or gas against the bottom of the piston 37 forces the rod section 33 to extended position. An air vent 39 is formed in the side of the intermediate section below the 45 cap 31 and vents the interior of the intermediate section to the atmosphere so that the piston will not compress air ahead of it against the cap 31 when moving upwardly under the urge of incoming compressed air or gas.

50 A soft rubber gasket 39 is disposed on top of the cap 31 of the intermediate section and forms a bumper to receive the ball 34 without shock and also prevents access of rain and other moisture of the interior of the intermediate section 20.

55 In operation the mast antenna constructed as above described is ordinarily carried in the telescoped position preferably with the radio receiver connected to it in operative position to receive calls at all times. Upon receipt of a call that 60 requires an answer, or in the event it is desired

to transmit a call, the vehicle operator merely extends the antenna to the proper height by admitting compressed air or gas to the interior of the antenna, and at the completion of the communication the fluid pressure medium may be 5 withdrawn from the antenna to permit the antenna to immediately gravitate to its normal telescoped position.

From the above description it is thought that the construction and operation of the invention 10 will be fully understood without further explanation.

What is claimed is:

1. A radio antenna for motor vehicles comprising a hollow body, a rear bumper mounting 15 bracket fixed to and insulated from the body, a tubular connection on the body for admitting a motive fluid to the body, a tubular intermediate member telescopically engaged in the upper end of the body, a piston carried by said member 20 engaging the body and against which said motive fluid exerts pressure to extend said member vertically from the body, a bushing in the lower end of the member having means for securing said piston in position and having an axial opening 25 of less diameter than the diameter of the member to permit restricted escape of the motive fluid from the body into said member, a tip member 30 telescoping into said intermediate member, a piston on the tip member engaging the intermediate 30 member and against which motive fluid acts to extend the tip member vertically, and respective ports in the body and in the intermediate member venting the body and member to the atmosphere above the intermediate member piston and above 35 the tip member piston respectively, and preventing the pistons from compressing air ahead of them when moving upwardly.

2. A radio antenna for motor vehicles comprising a hollow body, means for mounting the body in vertical position, means for admitting a motive fluid to the body, a hollow intermediate member telescopically engaged in the body, a piston carried by the lower end of said member, there being a restricted axial opening in the piston 40 permitting escape of the motive fluid from the body into the intermediate member, a sleeve on the intermediate member above the piston adapted to engage the upper end of the body for limiting upward movement of the member, said sleeve also weighting the member to promote quick gravitation thereof when the motive fluid is withdrawn therefrom, a tip member telescopically engaged in the intermediate member, a piston on the tip member against which the motive fluid in the intermediate member acts to extend the tip member, a sleeve on the tip member above the piston for performing the dual function of a stop to engage the upper end of the intermediate member and limit extending movement of the 45 tip member and also forming a weight to promote quick gravitation of the tip member when the motive fluid is withdrawn, and vents disposed near the upper ends of the intermediate member and the body venting the interiors of the intermediate member and the body and preventing the pistons compressing air ahead of them during their upward movement.

JOHN M. BEAUFORT.
